FLUID MOTOR

Henry C. Hueber, Snyder, N. Y., assignor to Trico Products Corporation, Buffalo, N. Y.

Application November 13, 1940, Serial No. 365,493

9 Claims. (Cl. 121—1)

This invention relates to a fluid motor and especially to a motor which is operated by suction, such as is found in the present day windshield cleaner installation on motor vehicles. In such installation a motor chamber at one side of its piston is connected to a source of suction such as the intake manifold of the vehicle engine and its opposite side connected to the atmosphere for creating a pressure differential sufficient to move the piston in one direction and upon the completion of this stroke of the piston the pressure differential is reversed, as by means of an automatic valve mechanism so as to effect a reverse stroke of the piston. As the outside atmosphere enters the valve compartment, containing the automatic valve mechanism, considerable noise is engendered which, in the quiet operation of the present day automobile, is quite noticeable and therefore undesirable. Furthermore, foreign particles are frequently inhaled by the motor which cause undue wear and eventually impair the efficiency of the motor.

The object of the present invention is to provide practical means for filtering the air as it enters the motor as well as eliminating any noise incidental to the passage of the inflowing air.

The invention further resides in a construction by which the filtering means are rendered self-cleaning and so disposed as to be readily accessible for repair or adjustment.

In the drawing:

Fig. 1 is a side elevation of a well-known type of windshield cleaner motor constructed in accordance with the present invention and having the valve chamber cover removed;

Fig. 2 is an end elevation of the motor;

Fig. 3 is a fragmentary transverse sectional view through the motor; and

Fig. 4 is a cross sectional view through the valve chamber taken about on line 4—4 of Fig. 2.

Referring more particularly to the drawing, the numeral 1 designates a motor housing having a chamber 2 in which operates a piston 3 which is fixedly carried by a shaft 4 to oscillate therethrough a double crank arm 5. The motor is provided with a nipple 6 designed for being connected by a conduit to a suitable source of suction. This nipple communicates with a suction supply port 7 in a valve seat 8 which port is connected by a valve 9 first to one and then the other of a pair of chamber ports 10 also in the valve seat 8. The two chamber ports communicate with the motor chamber 2 at respectively opposite sides of the vane-like piston 3, the unconnected one of the chamber ports being uncov-

ered by the valve 8 for admitting the atmospheric pressure to its side portion of the chamber. In prior constructions the atmospheric pressure has entered the valve chamber or compartment 11, defined by the upstanding side wall 12 on the exterior side of the motor housing, through a restricting orifice, as shown in Patent No. 2,032,319 granted February 25, 1936, to E. C. Horton and H. Hueber, or by slippage beneath the chamber closure which has produced a wheezing or whistling noise to the annoyance of the occupants of the vehicle.

In accordance with the present invention the inflowing air stream is caused to pass first through a fibrous or porous filter body 14, such as felt, which is disposed within a filter chamber 13 provided on the outside of the motor housing. The filter chamber is located adjacent the valve chamber, the same being partitioned therefrom by a wall 15. A wall 16 forming an extension of the partition 15 lies in opposition to the side wall 11 of the motor housing and defines the chamber 13 while the ends of such filter chamber are closed by walls 18 from opposed portions of the side wall. This leaves the chamber open only at its lower side through which the filter body is inserted. The partition wall is formed with one or more openings 19 through which the air enters the valve chamber after first passing through the filter. The overhanging wall 16 forms an offset extension of the floor or bottom wall of the valve chamber to provide support for the post 20 on which the pressure plate 21 of the valve mechanism is suspended, the valve mechanism depicted being similar to that disclosed in the aforesaid patent. A cover plate 21 encloses the automatic valve mechanism, being secured in position by a pair of screws 23 engaging in threaded openings 24.

One or more retaining pins 25 are passed downwardly through ears 26, formed on the inner face of the chamber wall to hold the filter body under compression and against freely expanding outwardly beyond the confines of chamber 13. By reason of the tendency to expand, the filter body subjects the pins to a lateral pressure sufficient to cause the pins to bind upon their supporting ears 26 against accidental dislodgement therefrom when the valve chamber cover 21 is removed, it being noted that the latter when in place overlies the ear openings.

By reason of the novel formation and location of the filter chamber beneath a portion of the valve chamber, the filter is protected while at the same time a large surface area of the filter

body is exposed to the air stream to permit movement of the latter in an ample volume for the efficient functioning of the motor. The filtered particles will collect on the exposed surface of the filter body and may therefore readily become dislodged by gravity or by the vibration of the vehicle during travel.

It will be understood further that the construction illustrated and described is merely illustrative of the inventive principles involved, which may be applied to other physical embodiments without departing from the scope and spirit of the invention claimed.

What is claimed is:

1. A fluid operated windshield cleaner motor having a body with an exteriorly provided valve compartment the floor of which has one portion offset outwardly from the exterior wall of the motor body to overhang the same in spaced relation and form therewith a chamber separated from the compartment by a partition, the partition having an air opening, and an air filter body disposed in the chamber to filter the inflowing air.

2. A suction operated motor having a casing, an upstanding wall on the outer side of the casing defining a valve compartment, a cover for the compartment, a pair of opposed end walls forming with the upstanding wall a chamber, the latter open on one side to the outside atmosphere and having air communication with the compartment, and a porous air filter body confined in the chamber between the end walls.

3. A suction motor having a casing with an exteriorly arranged compartment, automatic valve mechanism in the compartment, a wall of the compartment being provided with an air inlet opening, an open chamber about the air inlet opening, and a fibrous body inserted in the chamber for filtering the air and dampening the noise of passing through the air inlet opening, said fibrous body being exposed through the open chamber for easy dislodgment of foreign matter therefrom.

4. An air motor having a casing with an exteriorly arranged valve compartment for housing the automatic valve mechanism, a filter chamber adjoining the compartment and separated therefrom by an angular wall, said cham-

ber having restricted air communication with the compartment, a filter body arranged in the chamber about the angular wall and over the air communication, and means for securing the filter body against the angular wall.

5. An air motor having a casing with a valve compartment, the latter having an outwardly offset bottom wall defining with the casing a chamber which is open at one side, and a filter body disposed in the chamber, said chamber having air flow communication with the compartment.

10 6. An air motor having a casing with a valve compartment, the latter having an outwardly offset bottom wall defining with the casing a chamber which is open at one side, a filter body disposed in the chamber, said chamber having air flow communication with the compartment, and a retaining pin passed downwardly through the bottom wall into engagement with the filter body to hold the latter against displacement through the open side of the chamber.

20 7. A fluid motor having a casing with an exteriorly arranged valve compartment for its automatic valve mechanism, the compartment having a marginal portion overhanging the casing wall in outwardly spaced relation to define therewith a chamber, a fibrous body inserted in the chamber, the latter having air communication with the valve compartment, and means for retaining the fibrous body in its chamber.

25 8. An air motor having a casing with a valve compartment, the latter having an upstanding angular wall and opposed end walls defining with the casing a chamber which is open at one side, and a filter body disposed in the chamber, said chamber having air flow communication with the compartment.

30 9. An air motor having a casing with a valve compartment, the latter having an outwardly offset bottom wall defining with the casing a chamber which is open at one side, an expandible filter body disposed in the chamber, said chamber having air flow communication with the compartment, and a retaining pin slidably passed downwardly through an opening in the bottom wall into engagement with the filter body to hold the latter under compression whereby to bind the pin against displacement.

HENRY C. HUEBER.
